United States Patent Office

Des. 183,778
Patented Oct. 21, 1958

183,778

PORTABLE BEVERAGE DISPENSER

Richard K. Wentz, Baltimore, Md., assignor to Aircraft
Armaments, Inc., Cockeysville, Md., a corporation of Maryland

Application April 6, 1955, Serial No. 35,393

Term of patent 14 years

(Cl. D2—3)

FIG. 1

FIG. 2

I claim:

The ornamental design for a portable beverage dispenser, as shown.
